FIG. 1^B

UNITED STATES PATENT OFFICE

2,042,336

DEEP WELL PUMP

William H. Graham, Elko, Nev., and William S. Grau, Los Angeles, Calif., assignors to Graham Simplex Pump Company (no stockholders liability), Santa Fe, N. Mex., a corporation of New Mexico

Application April 9, 1934, Serial No. 719,730

6 Claims. (Cl. 74—59)

This invention relates to deep well pumps and more particularly to the type disclosed in my (William H. Graham) United States Letters Patent Number 1,834,024 issued December 1, 1931, 5 wherein a rotary driving member, a plunger pump and means for changing the motion of the rotary driving element to reciprocatory plunger operating motion; are readily lowerable into, operable within and removable from the well as a complete 10 plunger pump unit.

This invention is primarily intended for use in deep well pumping operations, as for instance that of oil wells, wherein a pump of the plunger type (not shown) is utilized and driven by rotary power means, such as an electric motor (not shown) "submerged" with and as part of the pump unit.

The primary object of the invention is to provide an association of parts so devised as to reliably function within the transversely limited dimension of deep well structures.

Another object is to provide a means in a plunger pump of the above character for changing the motion of the rotary driving element to reciprocatory plunger operating motion through the medium of clutches actuated by a control rod which in turn is controlled by reciprocation of a plunger rod, in which compression springs are employed in effecting movement of the control rod, 30 under accumulated tensioning of the springs, and in which detent means are provided for locking the springs against action and in which the detent means is positively actuated to release the springs at definite points in the travel of the plunger rod. 35 With the above and other objects in view the invention subsists in the novel construction and combination of parts hereinafter described, illustrated in the accompanying drawings, and set forth in the claims hereto appended, it being 40 understood that various changes in form, proportion, size and minor details of construction within the scope of the claims may be resorted to without departing from the spirit or sacrificing any of the advantages of the invention.

45 In the drawings:

Fig. 1A (sheet 1) is a view in section and elevation of the upper portion of the mechanism:

Fig. 1B (sheet 2) is a view in section and elevation of the lower portion of the mechanism and 50 which figure is readable in conjunction with Fig. 1A:

Fig. 2 is a view in horizontal section and plan as seen on the line 2—2 of Fig. 1A:

Fig. 3 is a view in section and plan as seen on 55 the line 3—3 of Fig. 1A:

Fig. 4 is a view in section and plan as seen on the line 4—4 of Fig. 1A:

Fig. 5 is a view in horizontal section and plan taken on the line 5—5 of Fig. 1B:

Fig. 6 is a view in horizontal section and plan 5 as seen on the line 6—6 of Fig. 1B:

Fig. 7 is a view in horizontal section and plan taken on the line 7—7 of Fig. 1B:

Referring to the drawings: 10 indicates a sealed casing within which the working parts of the 10 pump are operated in a suitable lubricant. At one extremity of the casing 10 are double clutch members A—A' and the associated parts for driving and utilizing the clutch power. The preferred form of the double clutch is that of the disk type 15 conventional in mechanism and operation and requiring no further description.

The clutch ensemble is mounted axially concentric in the casing 10 and surrounding the plunger rod 11 which, in the preferred form, is tubular and 20 subsequently more fully described.

The clutch members A—A' are respectively housed in the shroud bevel gears 12 and 13 the internal surfaces 14 and 15 of the shrouds being grooved longitudinally to receive the lugs of alternate clutch disks in the usual manner. The shroud 12 of the clutch member A is prolonged by the sleeve shaft 16 and terminates in the jaw clutch 17.

Within and closely fitting the bore of the casing 30 10 is mounted the cage 18 secured against axial rotation in the casing 10 by suitable means as the screws 19. The cage 18 is provided with suitable seats for mounting the outer race of the roller bearings 20 and 21. The inner races of the bearings 20 serve to mount, freely rotatable therein, the sleeve shaft 16 of the shroud bevel gear 12. In like manner the bearings 21, the inner races of which are mounted on the sleeve extension 22 of the shrouded bevel gear 13, mount this gear, 40 45 and the clutch disks rotated thereby, in a freely rotatable manner. Intermeshing with the shroud gears 12 and 13, and as mounted on the relatively fixed bearings 23 in the cage 18, the bevel gears 24 effect a reversal of the direction of rotary motion in the gears 12 and 13 with respect of each to the other. As will be noted the gears 24 occupy a symmetrically radial disposition, Figure 3, in thirds, thus providing space for the clutch actuating connectors later described.

The plunger rod 11 is externally threaded; the thread 25 being of suitable proportions as to pitch, lead and character, for a longitudinal distance equalling the desired length of the plunger rod stroke. As illustrated the plunger rod 11 is shown 50 55

nearing the end of the "up" stroke the additional travel thereof being that required to actuate the clutch operating mechanism later described.

Surrounding the plunger rod 11 is positioned 5 the sleeve nut 26, internally threaded as a counterpart of the thread 25 on the plunger rod 11. The sleeve nut 26; of a length desirable to obtain the requisite working length and strength of threads to sustain the imposed loads and power 10 output, is journaled freely rotatable in the bearing bores 27 and 28 formed in the sleeve extensions 16 and 22 of the shroud bevel gears 12 and 13.

The sleeve nut 26, further acts as a sleeve shaft 15 upon which the clutch members are mounted in a conventional manner. The disks of the clutch members A—A'; as laminations alternating those secured to the shroud bevel gears 12 and 13 as above described, are connected in the usual manner (lug and spline means 29) to the sleeve nut 26. It is apparent; that, in the neutral position 20 of the clutch throw members, the body of the clutch journaled on the sleeve nut 26 and the clutch disks, spline and lug mounted, on the sleeve nut and the nut itself are freely rotatable in either direction with respect to the gears 12 25 and 13 and their associated clutch disk members. Briefly, the sleeve nut 26 may be driven by either 30 of the gears 12 or 13 in opposite rotary directions as effected by engagement of the respective clutch members.

The extension sleeve shaft 16 of the gear 12 is 35 sufficiently prolonged to accommodate the insertion of the head 30, threaded at 31 into the end of the tubular cage 18. The head 30 is provided with the bore 32 in which the shaft 16 is freely 40 rotatable and packed or sealed by suitable means as the felt washer 33. The compartment formed in the casing 10 by the cage 18, and the assembled parts described, is sealed at the bottom by the head 34 threaded at 35 into the cage 18. The head 34 is provided with the bore 36 sealed, by suitable means as the felt washer 37. The head 34 is further sealed relative to reciprocating parts 45 of the clutch operating mechanism, later described, by suitable means as the felt pads 38.

It is apparent that the compartment, sealed as described, inclosing the gear transmission may be filled with the proper lubricant for operation of the parts.

50 The lower end of the sleeve extension 22 of the bevel gear 13 terminates in the threaded portion 39 upon which is mounted the threaded cup bearing housing 40 having the projecting portion or skirt 41, which passes through the bore 36 55 in the head 34. The downward thrust of the sleeve nut 26, effecting the heavy duty upthrust stroke of the plunger rod 11, is sustained by the ball thrust bearing 42 interposed between the lower end of the sleeve nut 26 and the cup bearing housing 40. As this cup bearing housing, shrouded bevel gear and sleeve extension are 60 constituted as a unit part, the load imposed on the ball thrust bearing 42 is in turn, transmitted to and is sustained by the roller bearings 21 mounted 65 in the cage 18.

As described, alternating the clutch mechanism to engage and disengage the respective clutch members A and A' causes the sleeve nut 26 to 70 rotate in alternately reversed directions which, in turn, causes the plunger rod 11, as a counterpart threaded member, to move rectilinearly in the casing 10 a longitudinal distance predetermined by the length of the thread on the plunger rod and the number of revolutions, in one or the 75 other direction, of the sleeve nut. The plunger

rod 11, as a non-threaded member and the clutch throw members 43 engaging the clutch slip ring 44 are prolonged to enter the compartment 45 in the casing 10, the former, to function as operating the trip-spring mechanism actuating 5 the latter as the clutch operating means.

For the purpose of effecting durability and strength these members, the trip-spring mechanism and the clutch throw members, are provided in triplicate, but as each is a counterpart 10 of the other a disclosure and description of one will serve for the others.

Within the casing 10 is mounted the cage 46 maintained therein against upward longitudinal movement by the spacer 47 between the head 34 15 of the clutch mounting cage 18 and the head 48 threaded at 49 in the cage 46. The cage 46 is maintained against longitudinal movement at the bottom of the casing 10 by the closure member 50 threaded at 51 into the casing 10 abutting the 20 head 52 threaded at 53 in the cage 46. This cage consists of an outer tube 54 substantially fitting the casing 10 and an inner tube 55 sufficiently larger than the plunger rod 11 to allow free longitudinal movement of parts thereof later 25 described. Both the outer tube 54 and inner tube 55 are slotted longitudinally with triplicate, radially symmetrical and aligned slots accommodating and guiding parts later described.

Within the cylindrical space formed by the 30 outer and inner tubes 54 and 55 of the cage 46 are positioned the detents or fingers 56 and 57, knuckle jointed; as by means of the clip 58 carrying the knuckle pin 59 and fixed to the heads 48 and 52 by the screws 60, to extend parallel to, 35 move and be impelled radially convergent relative to the longitudinal axis of symmetry of the structure. As a means impelling the fingers inwardly the springs 61 are provided, their base end 62 and 63 respectively encircling the rounded end 40 64 of the finger, and are recessed in the groove 65 which is further prolonged in the body of the finger to guide and maintain the spring in place. The resilient end 66 of the spring reacting against the inner surface of the cage 46 45 forces the finger inwardly and provision of the notches 67 and the beveled ends 68 complete the fingers for purposes later described.

In the longitudinal slots 69 of the outer tube 54 of the cage 46, which register longitudinally with 50 the like slots 70 in the cage 18, is positioned and guided for longitudinal movement therein, the clutch throw members 43. Each of these members comprise the yoke portion 71 engaging the clutch slip ring 44, the inwardly projecting lug 55 portion 72 and terminate, near the bottom of the cage 46, in the inwardly projecting lug 73. It is apparent that alternating longitudinal movement of the clutch throw members 43; predetermined as occurring in a cycle of time or distance, as 60 instanced by the length of the plunger rod stroke desired, will cause a declutching and clutching action of the clutch members A and A' in alternating sequence at definite points in the length of stroke of the plunger rod.

It is further apparent that to effect adequate longitudinal movement of the clutch throw members 43, functioning to declutch and clutch the clutch members A and A', as by means actuated by the movement of the plunger rod; stored 70 energy is requisite, as, at the moment of declutching, movement of the plunger rod ceases until the action of reclutching (for the reverse stroke of the plunger rod) is accomplished.

Within the upper end of the cage 46 and sur- 75

rounding the inner tube 55 and constituted freely slideable thereon by the bore 74, is positioned the upper follower B. At symmetrically radial positions on the body of the follower B, lugs 75 project upwardly and engage the radially registering slots 76 in the cage head 48 which serve as guides for longitudinal movement of the follower. The position of the lugs 75 is such as to radially align them with the clutch throw members 43 and as functioning to engage the lugs 72 on the respective clutch throw members. Beneath the follower B and secured thereto, as by means of the bolt clamps 77, is the compression coil spring 78 surrounding the inner tube 55. The body of the follower is provided with the flange portion 79 engaging the notch 67 in the detents 56. It is apparent that the extremities of the detent notch 67 which extend in parallel relation to each other and to the upper and lower surfaces of the flange 79 serve as positive limit stops of longitudinal movement of the follower.

Within the lower end of the cage 46 and surrounding the inner tube 55 and constituted freely slideable thereon by the bore 80, is positioned the lower follower B', provided with the flange 81 having the radial slots 82 engaging the detents 57 which serve as guides for longitudinal movement of the follower. The arcuate portions 83 of the flange 81 serve to engage the lugs 73 on the clutch throw members 43. The body of the follower B' is further provided with the flange portion 84 engaging the notch 67 in the detents 57. As, with respect to the upper follower, the extremities of the detent notch 67 extend in parallel relation to the upper and lower surfaces of the flange 84 and serve as positive limit stops of longitudinal movement of the lower follower. The counterbore 85, pockets the lower end of the compression coil spring 86 surrounding the tube 55.

At a point corresponding with the one or the other extreme of the plunger stroke relative to the followers B and B' the plunger rod is provided with the sleeve coupling 87 into which the respective ends of the rod are threaded and further secured in a suitable manner as by means of the set screws 88. The coupling is constructed to provide the spider arms 89 projecting radially, Figure 6, through the slots 90 in the tube 55. It is worthy of note, that the interaction of the coupling 87, spider arms 89 and the respective edges of the slots 90 in the fixed inner tube 55, coact to prevent rotation of the plunger rod and resist the torque action resulting from the revolution, under load, of the sleeve nut 26 on the plunger rod. To the outer ends of the spider arms 89 is secured, by suitable means as the tap bolts 91, the trip or ring cam 92 provided with the opposed beveled cam faces 93 and 94 adapted, upon sufficient longitudinal movement of the plunger rod, to act upon the respective beveled ends 68 of the detents 56 and 57 respectively and positively trip the detents by forcing them radially outward.

As described the casing 10 is sealed at its lower extremity by the head 50 threaded into the casing. The plunger rod extends through the bore 95 in this head and is sealed relative to ingress of the well contents by suitable means as the compression packing 96 in the stuffing box 97. The head 50 is externally threaded at 98 to accommodate prolongation of the casing serving to house additional elements, not shown, of the pump structure.

Operation is as follows: With relation to the

several elements of the structure as illustrated, the upper clutch member A effects the down stroke of the plunger rod, while that of the clutch member A' effects the up stroke of the plunger rod. This reciprocating motion of the plunger rod being effected as above described and briefly reiterated consists in the engagement of the threaded plunger rod 11 with the counterpart threaded sleeve nut 26 the latter being rotated in reversed directions by alternating engagement with the respective clutch members A and A'.

With the clutch member A' engaged and A disengaged, rotary motion and power in one direction applied to the jaw clutch 47, is transmitted to the bevel gear train, as idling through clutch A and as applied in clutch A'. Thus affected, the plunger rod tends to move upward to complete the up stroke. As illustrated the plunger rod carrying the trip cam 92 is shown nearing the end of the up stroke. At this position the trip cam effects contact with the lower end of the compression coil spring 78. Upon continued movement of the plunger rod compression of the spring occurs as the follower B is held against longitudinal movement, in the direction of the spring compression, by the detents 56 the upper end of the notch 67 of which engages the upper surface of the flange 79 of the follower. Upon further continued movement of the plunger rod the trip cam 92 effects contact with the beveled ends 68 of the detents whereupon a slight additional movement positively forces the detents radially outward, due to the action of the beveled surfaces of the detent and trip cam, thus releasing the follower. Upon release of the follower the power of the compressed spring 78 impels the follower to instantly move longitudinally, engage the lug 75 with the lug 72 of the clutch throw members 43 and exert power of sufficient magnitude and instantaneous effect to declutch the driving member A' and throw in the clutch A. As the clutch A effects the down stroke of the plunger rod it immediately begins to move downwardly. As this movement continues the trip cam is retracted free of contact with the detents which are again forced inwardly by their respective springs to their initial position. Upon still further movement of the plunger rod the compression spring assumes the form of its free length and, as retraction continues, lowers the follower to rest upon and be retained in its initial position by engagement with the lower end of the notch 67 in the detents.

The down stroke of the plunger rod in like manner effects a reversed movement of the clutch throw members as the follower B' is impelled downwardly, by the detent released compression spring 86, to make contact with the lug 73 of the clutch throw members 43 and actuate the clutch members A and A' in a vice versa manner.

It is apparent that continuous reciprocating motion of the plunger rod by the elements involved subsists in a declutching and clutching cycle operating in alternating sequence.

We claim:

1. In a deep well pump, a casing, a reciprocal plunger rod, a rotary drive member in said casing arranged concentrically with said plunger rod, means of operative connection between said drive member and said rod operative to reciprocate said rod on rotation of said drive member, spring impelled means for changing the direction of rotation of said drive member during each stroke of said rod, spring pressed detents controlling said spring impelled means, and means on said rod 75

for effecting positive actuation of said detents at predetermined points of travel of said rod to effect release of said spring impelled means.

2. In a deep well pump, a casing, a plunger rod, 5 a double clutch in the upper end of said casing, means of operative connection between said clutch and said rod operative to reciprocate said rod, clutch operating means in the lower end of said casing said means comprising respectively 10 opposed spring impelled followers detent held, and means on the said plunger rod to at each end of the plunger rod stroke successively compress the said spring and positively release the said detent and means imparting the resultant spring 15 actuated movement of the said followers to the said clutch.

3. In a deep well pump, a casing, a reciprocal plunger rod, a rotary drive member in said casing arranged concentrically with said plunger rod, 20 means of operative connection between said drive member and said rod operative to reciprocate said rod, drive member operating means in the lower end of said casing said means comprising respectively 25 opposed spring impelled followers detent held, and means on the said plunger rod to at each end of the plunger rod stroke to successively compress the said spring and positively release the said detent and means imparting the resultant spring 30 actuated movement of the said followers to the said clutch.

4. In a deep well pump, a casing, a rotary drive member in said casing, a plunger rod, means of operative connection between said drive member and said rod for reciprocating the latter, a pair 35 of clutches embodied in said means, a reciprocal sleeve adapted to alternately operate said clutches, control rods connected to said sleeve extending downwardly in said casing, a pair of spaced lugs on said rods, a guide tube encircling 40 said plunger rod, a pair of spaced followers slidably encircling said guide tube between said lugs, means on said followers arranged to engage said lugs, means positively engaging said followers to hold same against movement, means for positively 45 actuating said last named means to release said followers, and springs arranged to actuate said

followers on release thereof to advance said clutch control rods.

5. In a deep well pump, a casing, a rotary drive member in said casing, a plunger rod, means of operative connection between said drive member and said rod for reciprocating the latter, a pair 5 of clutches embodied in said means, a reciprocal sleeve adapted to alternately operate said clutches, control rods connected to said sleeve and extending longitudinally of said casing, a pair of 10 spaced lugs on said rods, a guide tube encircling said plunger rod, a pair of spaced followers slidably encircling said guide tube between said lugs, means on said followers arranged to engage said lugs, trip means positively engaging said followers to hold same against movement, means for positively actuating said trip means to release said followers, and springs arranged to actuate said followers on release thereof to advance said clutch control rods, said springs being arranged 20 between said trip actuating means and said followers and adapted to be engaged and compressed by said trip actuating means.

6. In a deep well pump, a casing, a rotary drive member in said casing, a plunger rod, means of 25 operative connection between said drive member and said rod for reciprocating the latter, a pair of clutches embodied in said means, a reciprocal sleeve adapted to alternately operate said clutches, control rods connected to said sleeve 30 extending downwardly in said casing, a pair of spaced lugs on said rods, a guide tube encircling said plunger rod, a pair of spaced followers, spring pressed detents having notches formed 35 with parallel end walls engageable with said followers to positively hold the followers against movement, a trip ring carried by said piston rod arranged to positively engage and trip said detents out of engagement with said followers, and springs encircling said guide tube bearing against 40 said followers and arranged to be placed under compression by advance of said trip ring to the detent releasing position.

WILLIAM H. GRAHAM. 45
W. S. GRAU.
